UNITED STATES PATENT OFFICE.

EMIL BLOSSFELD, OF SAN FRANCISCO, CALIFORNIA.

SASH-LOCK.

971,350.

Specification of Letters Patent. Patented Sept. 27, 1910.

Application filed November 29, 1909. Serial No. 530,293.

To all whom it may concern:

Be it known that I, EMIL BLOSSFELD, a citizen of the United States, residing in the city and county of San Francisco and State 5 of California, have invented new and useful Improvements in Sash-Locks, of which the following is a specification.

My invention relates to window locks or sash locks. Its object is to provide a simple, 10 practical locking device, which can be readily attached to any window, and by which the sashes may be locked together, either in open or closed position, and which will regulate and limit the opening at top and bottom 15 of the window in case ventilation is desired.

The invention consists of the parts and the construction and combination of parts as hereinafter more fully described and 20 claimed, having reference to the accompanying drawings, in which—

Figure 1 is a front elevation of the device, attached to a window, with the sashes shown in closed position. Fig. 2 is a similar view 25 with the sashes partly open. Fig. 3 is a top plan view corresponding to Fig. 1. Fig. 4 is a top plan view corresponding to Fig. 2. Fig. 5 is a section on $x-x$ Fig. 1. Fig. 6 is a section on $y-y$ Fig. 2; (Figs. 1, 3 and 5 being 30 read together, and Figs. 2, 4 and 6 being read together.)

A represents the upper sash, and B the lower sash of a window, to which the invention is applicable.

35 In the embodiment of the invention, as here illustrated, 2 is a casting or plate secured to the top rail of the lower sash, and 3 is a casting or plate secured to the bottom rail of the upper sash.

40 4 is a rod of suitable length and material, with one end bent to fit and freely turn in a suitable journal 5 in the sash plate 3; the main portion of the rod 4 being straight, and at right angles to the portion pivoted 45 in the bearing 5, and the straight portion slidable in the U-shaped gripping portion 6 of the clamp screw 7, which latter passes through a guide or bearing 8 in plate 2 and is threaded to be engaged by a locking 50 nut 9.

The free end of the rod 4 is bent, or otherwise fashioned to form a head 10 to prevent its being withdrawn from the U clamp 6.

55 As here shown the rod 4 is normally free to swing in a plane parallel with the sashes.

In operation the two plates 2-3 are se-

cured on the adjacent sash rails. If it is desired to leave the windows free so that they can be opened independently, and to their full limit, or otherwise be moved up 60 and down freely and independently, the rod 4 is disengaged from the clamp member 6, this disengagement being readily effected by suitably slackening up or pushing in on the nut 9 so that the rod 4 can be sprung out 65 through the open side of the U clamp 6. If it is desired though to utilize the lock, the rod is engaged with the clamp, as shown in Fig. 6, and when so engaged the sashes are free to move up and down within the limits 70 of the length of the rod 4.

If it is desired to hold the window open, either from top or bottom, and to maintain the sides of the opening temporarily fixed, it is only necessary to screw up on the nut 9, 75 which has the effect of drawing up on the clamp 6 to grip the rod 4 against the end of the bearing-block 8. Likewise the windows are locked in closed position by first closing the window, and then tightening the screw 80 9, as shown in Fig. 1.

While I have shown the device attached to the upper and lower rails of two sashes, it is manifest that it can be applied in other ways. It can be applied to single sliding windows 85 by simply attaching one plate 2 to the window frame, and the other plate 3 to the sliding sash.

It is possible that various changes and modifications may be made in the form of 90 the device without departing from the principle of the invention.

As a means of quickly releasing the grip 6 from the rod 4 so that either window may be run up or down independently of the locking 95 rod 4, I provide a loose collar 11, which slides free upon the screw 7 between the thumb-screw 9 and a spiral spring 12. The spring 12 acts against a fixed stop and against the collar 11 to exert an inward pull 100 upon the hook 6. By pressing in upon the thumb-screw 9, the collar 11 slides into the housing 8 and compresses the spring 12 and allows the hook 6 to be disengaged from the bar 4.

Having thus described my invention, what I claim and desire to secure by Letters Patent is—

1. In a sash lock, the combination with a movable sash, a plate secured to a suitable point of support, a rod pivotally connected to said plate to swing in a plane parallel 110

with the sash, a plate secured to the upper rail of said sash, and having a slidable spring-pressed clamp member engageable with said rod.

- 5 2. In a sash lock, the combination with a movable sash, a plate secured to a suitable point of support, a rod pivotally connected to said plate to swing in a plane parallel with the sash, a plate secured to the upper rail of
- 10 said sash having a clamp member engageable with said rod, said clamp member comprising a slidably-mounted screw-threaded bolt having a U-shaped portion open at one side and adapted to embrace the rod and a
- 15 clamp screw operative on the bolt.

3. In a window lock, the combination with movable sashes, of an outwardly spring-

pressed hook member carried by one of the sashes and slidably transversely of one of the rails thereof, a pivoted rod carried by the 20 other sash and engageable and disengageable with said hook member, and means for operating the hook member either to clamp the rod or to compress the spring of said hook member and thereby cause the hook member 25 to release the rod.

In testimony whereof I have hereunto set my hand in the presence of two subscribing witnesses.

EMIL BLOSSFELD.
